UNITED STATES PATENT OFFICE.

DONALD BARNS MORISON, OF HARTLEPOOL, ENGLAND.

APPARATUS FOR DISCHARGING AERATED VAPOR FROM STEAM-CONDENSERS.

1,359,907.

Specification of Letters Patent. Patented Nov. 23, 1920.

Application filed August 12, 1916. Serial No. 114,635.

To all whom it may concern:

Be it known that I, DONALD BARNS MORISON, a subject of the King of Great Britain and Ireland, residing at Hartlepool, in the county of Durham, England, have invented Improvements in Apparatus for Discharging Aerated Vapor from Steam-Condensers, of which the following is a specification.

This invention relates to the discharge of aerated vapor from a steam condenser under vacuum by means of steam operated ejectors.

The weight of air in the mixture of aerated vapor to be discharged from a steam engine condenser under vacuum varies. For example, the weight of air will vary with variations in the quantity of steam condensed; also, the air entering the vacuum system often increases beyond the normal by insidious leakage through joints and connections.

When discharging aerated vapor against a pressure, and especially against a considerable pressure, by means of a steam operated ejector, it is known that unless the combining tube into which the steam jet discharges is sufficiently filled, the uniformity and continuity of flow through the tube is disturbed and the tendency for instability and back flow is increased.

In order to overcome this defect in steam jet ejector apparatus when used in connection with steam engine condensers, it is known to introduce or produce somewhere in the ejector system between the condenser and the atmosphere such additional air or steam as may at any time be necessary to insure the required uniformity of flow in the combining tube. This method has, as a result, that whenever such additional supply is necessary the cross sectional area of the combining tube without such additional supply would be unduly large, and instability of flow would result. But the cross sectional area of a combining tube determines under given conditions the quantity of steam used in the jet, therefore the employment of a combining tube which requires an additional supply to insure uniformity of flow and the stability of the vacuum, necessitates an increased expenditure of steam in the steam jet.

For example, suppose a steam engine exhausts 100,000 pounds of steam per hour

into a high vacuum condenser, and that the quantity of free air to be discharged from the condenser, assuming that the joints and connections under vacuum are practically air tight, is about 6 cubic feet per minute at atmospheric pressure at say 60 degrees Fahrenheit. The possibility of air leakage into such a plant is very considerable, and as air leaks are often difficult to locate and as air is highly detrimental to condenser efficiency, it is obviously wasteful to employ a final steam ejector capable of discharging considerably more than the normal quantity of air.

The object of my invention is to promote stability in the working of steam operated ejectors arranged in series for discharging from a steam condenser aerated vapor containing varying quantities of air.

For this purpose, in apparatus comprising steam operated ejectors arranged in series, stability in working is promoted, in accordance with my invention, by constructing the last or final ejector of the series in the form of multiple discharging units arranged to operate in parallel, each discharging unit consisting of a steam operated ejector which is of such air discharging capacity that by the selection of any one of the units, or by the combination of two or more of the units, the capacity of the apparatus for the discharge of air can be determined for a given quantity of air, or can be increased from a predetermined small quantity to a predetermined large quantity by one or more successive increments, or vice versa. With such apparatus, and by the judicious selection of a unit or combination of units, stability in working can be maintained without any supplementary supply of air to the vacuum system.

The passage or passages to or from one or more of the ejectors and the supply to the steam jets, are fitted with valves or cocks suitable for operation by hand or automatically, so that one or more of the ejectors may be brought into use when desired. The capacities of the ejectors may vary in any desired manner, or they may be equal, depending on the requirements of any particular plant.

The accompanying drawings illustrate convenient forms of my invention which is

employed as the last or final ejector in a series of ejectors which discharge aerated vapor from a steam condenser under vacuum. In Figure 1, three ejectors are shown arranged in series with intermediate condensers, the third or last ejector of the series being constructed in accordance with my invention, and consisting of three discharging units. In Fig. 2, two ejectors are shown in series with intermediate condensation, the second or last ejector consisting of two discharging units in accordance with my invention. Fig. 3 is a modification of Fig. 2, the second or last ejector consisting of three discharging units.

In Fig. 1 my invention comprises multiple final ejectors, c , c^1 , c^2 , arranged in parallel with each other and in series with the ejectors a and b , e and f being intermediate condensing receivers. The passages from the ejectors c , c^1 , c^2 , namely, the combining tubes l , l^1 , l^2 , are provided with cocks o , o^1 , o^2 and the steam supply to the ejectors is provided with valves m , m^1 , m^2 , so that one or more of the ejectors may be brought into use when desired. The ejectors c , c^1 , c^2 may each have any suitable air capacity, and in the arrangement illustrated they are designed for capacities for discharging respectively 1, 2 and 4 pounds of air, contained in the aerated vapor withdrawn from the condenser d , per unit of time, and may be operated in the following manner.

	<i>Ejectors in operation.</i>	<i>Capacity of each ejector.</i>	<i>Total capacity.</i>
	c	1	1
	c^1	2	2
	$c+c^1$	1+2	3
	c^2	4	4
40	$c+c^1+c^2$	1+4	5
	c^1+c^2	2+4	6
	$c+c^1+c^2$	1+2+4	7

By these means of selection or combination the capacity of the final discharging apparatus can be increased by such increments as will enable stability to be maintained throughout a large range of air quantities, and the air can be discharged with a highly economical expenditure of steam.

In the apparatus described, the ejectors a and b may be constructed and operated in the manner described with reference to the air withdrawing and controlling ejectors illustrated in the specification of my application Serial Number 89,459, filed April 6, 1916, and the final discharging apparatus comprising the three ejectors c , c^1 , c^2 , may work under a pressure difference such as is indicated with reference to the air delivery ejector described in my prior specification referred to.

Fig. 2 is a modification of Fig. 1 and shows multiple final ejectors c and c^1 in series with a single ejector b and intermediate condenser f .

Fig. 3 is a further modification of the arrangement illustrated in Fig. 1, and shows a single steam ejector b and condensing receiver f in combination with multiple units c , c^1 , c^2 , each of which comprises steam jets in series without intermediate condensation, m and n being the steam supply valves to the respective jets.

What I claim is:—

1. In apparatus comprising steam ejectors arranged in series for discharging aerated vapor from a steam condenser, promoting stability in working by constructing the last ejector of the series in the form of multiple discharging units arranged in parallel, each unit consisting of a steam operated ejector, the combining tube or discharge pipe of each unit being provided with a cock having a plug the port of which when in its open position is coincident with and forms part of the combining tube or discharge pipe, means being provided whereby the steam supply to each unit can be regulated, thereby enabling one or more of said units to be brought into operation depending on the volume of the aerated vapor to be withdrawn from the condenser.

2. In apparatus comprising steam ejectors arranged in series for discharging aerated vapor from a steam condenser, promoting stability in working by constructing the last ejector of the series in the form of multiple discharging units arranged in parallel, each unit consisting of a steam operated ejector, the combining tube or discharge pipe of each unit being provided with a cock having a plug the port of which when in its open position is coincident with and forms part of the combining tube or discharge pipe, means being provided whereby the steam supply to each unit can be regulated, the said ports of each cock being of differential capacities thereby enabling one or more of said units to be brought into operation depending on the volume of the aerated vapor to be withdrawn from the condenser.

3. In combination a steam condenser, a steam operated ejector operating to withdraw aerated vapor from said condenser, an intermediate condensing receiver to which said ejector discharges, a second ejector operating to withdraw aerated vapor from said intermediate condensing receiver, a second intermediate receiver to which said second ejector discharges, a final ejector comprising a plurality of ejector nozzles each of different capacity arranged in parallel relation to each other and in series with said first and second ejectors and their associated con-

densing receivers, a cock in each combining tube of each unit having a plug the port of which when in its open position is coincident with and forms part of the combining 5 tube or discharge pipe and means whereby the steam supply to each unit can be regulated.

Signed at London this 29th day of July, 1916.

DONALD BARNES MORISON.
